SELF-LOADING DEVICE FOR SHAKER CONVEYERS

William W. Sloane, Chicago, Ill., assignor to Goodman Manufacturing Company, Chicago, Ill., a corporation of Illinois

Application May 20, 1943, Serial No. 487,683

11 Claims. (Cl. 198—220)

This invention relates to improvements in self-loading devices for shaker conveyers of the type utilized for picking up loose material such as coal, rock, or the like from the ground, in mines underground.

The principal objects of my invention are to provide a novel and simplified form of self-loading device for a shaker conveyer, including a simplified form of guide means forming guide and reaction members for a pair of draft devices, for swinging the pick-up end of a shaker conveyer laterally along the ground by power.

The device of my present invention is somewhat similar to that shown and described in a patent, No. 2,280,043, which issued to Loy D. Hagenbook on April 14, 1942, and in an application, Serial No. 461,119, filed by Loy D. Hagenbook on October 7, 1942, now Patent No. 2,343,144, but differs therefrom in that the extensible trough is supported directly on the ground and the usual heavy supporting base and guide frame for the reciprocating and extensible troughs are eliminated.

Other objects of my invention will appear from time to time as the following specification proceeds and with reference to the accompanying drawings wherein:

Figure 1 is a plan view of a loading device constructed in accordance with my invention;

Figure 2 is an enlarged view in side elevation of the forward part of the loading device shown in Figure 1, with certain parts shown in longitudinal section;

Figure 3 is an enlarged plan view of the forward part of the loading device shown in Figure 1, with certain parts broken away and certain other parts shown in horizontal section;

Figure 4 is an enlarged plan view of the rear part of the loading device shown in Figure 1, with certain parts broken away and certain other parts shown in horizontal section;

Figure 5 is an enlarged fragmentary view in side elevation of the rear part of the loading device shown in Figure 1, with certain parts broken away and certain other parts shown in longitudinal section;

Figure 6 is an enlarged view of the rear end of a guiding member for one of the flexible draft devices, with certain parts shown in longitudinal section, in order to show certain details of construction thereof;

Figure 7 is an enlarged sectional view taken substantially along line 7—7 of Figure 4;

Figure 8 is a sectional view taken substantially along line 8—8 of Figure 4;

Figure 9 is a sectional view taken substantially along line 9—9 of Figure 4;

Figure 10 is a fragmentary transverse sectional view taken substantially along line 10—10 of Figure 3;

Figure 11 is a transverse sectional view taken substantially along line 11—11 of Figure 3;

Figure 12 is an enlarged detail view of the forward end of a guiding and reaction member for one of the flexible draft devices, showing certain details of the support therefor on the reciprocating trough section; and

Figure 13 is an enlarged plan view of the forward end of a guiding and reaction member for one of the flexible draft devices, with certain parts broken away and certain other parts shown in horizontal section, in order to more clearly show certain details of construction thereof.

The embodiment of my invention illustrated in the drawings includes generally an extensible trough 10 having a shovel 11 on its forward end, slidably supporting the forward end of said trough on the ground and adapted to pick up loose material from the ground. Said extensible trough is supported on the ground at its rear end on a ground-engaging shoe 13 by means of a pair of laterally spaced supporting legs 14, 14, transversely pivoted to said shoe at their lower ends and extending upwardly along the outer sides of a swiveled or reciprocating trough 15. Said supporting legs are secured at their upper ends to the rear ends of a pair of bearing plates 16, 16, secured to and projecting laterally from the upper outer sides of said extensible trough, and extending therealong.

The bearing plates 16, 16 also form a supporting means for the forward end of the reciprocating trough 15 and are adapted to be slidably engaged by a pair of vertically spaced bearing blocks 19, 19, pivotally mounted on opposite upright sides 20, 20 of a support frame 21, which is secured to and extends across the bottom of and upwardly along opposite sides of the forward end of said reciprocating trough.

The bearing plates 16, 16 are also adapted to be engaged by grip blocks 23, 23 mounted in carrier members 24, 24 of a friction grip feeding device 25. Said feeding device may be of any well known form but is herein shown as being of a type somewhat similar to that shown and described in my prior Patent No. 2,318,808 dated May 11, 1943, and includes generally the two carrier members 24, 24, each of which has a pair of the friction grip blocks 23, 23 pivotally mounted thereon and adapted to have gripping en-

gagement with the upper and lower sides of the bearing plates 16, 16, during certain strokes of the conveyer.

The upper end of each carrier member is connected with the support frame 21 by means of a link 26, having connection with a frame 27 transversely pivoted to and extending forwardly from the support frame 21. A yieldable link 28 connects the lower end of each of said carrier members with said transversely pivoted frame. When said upper links 26, 26 are locked to reciprocably move with the frame 27 and the reciprocating trough 15, and the yieldable links 28, 28 are free to move with respect to said frame and trough, said links 26, 26 will exert a pulling force on the upper ends of said carrier members during the return strokes of the conveyer, to cause said friction grip blocks to grip said bearing plates during the return strokes of the conveyer, and will exert a force on said carrier member in an opposite direction during the forward strokes of the conveyer, to release said friction blocks from said bearing plates and retractably move said extensible trough with respect to said reciprocating trough.

When the yieldable links 28, 28 are locked to reciprocably move with the frame 27 and the reciprocating trough 15, and the links 26, 26 are free to move with respect to said frame and trough, a forward thrusting action will be exerted on the lower ends of said carrier members during the forward strokes of the conveyer, to engage the friction grip blocks 23, 23 with the bearing plates 16, 16, during the forward strokes of the conveyer, and an opposite force will be exerted on said carrier members during the return strokes of the conveyer, to release said grip blocks from said bearing plates, to extend said extensible trough with respect to said reciprocating trough.

The reciprocating trough 15 is mounted at its rear end on a base 29 of a swivel 30 in a manner which will hereinafter more clearly appear as this specification proceeds. Said swivel, as herein shown, includes a relatively short intermediate trough 31 having outwardly flared curved forward and rear ends 32 and 33, respectively. Said forward curved end has a flared curved rear end of a connecting trough 34 nested therein, which is connected to the rear end of the reciprocating trough 15. Said curved rear end of said intermediate trough is nested within a correspondingly curved flared receiving end of a connecting trough 34. Said connecting trough is secured to the forward end of a trough 35, which is secured to and forms a part of the inby end of the shaker conveyor trough line. Said swiveled intermediate trough is pivotally connected to said troughs 17 and 34 by means of pivotal bearing members 36 and 37, and forms a continuous trough from the reciprocating trough 15 to the trough 35, when the extensible and reciprocating troughs are displaced laterally at various angular positions with respect to the conveyer trough line about the vertical axes of the bearing members 36 and 37.

The bearing member 36 is pivotally mounted on a transverse frame 39 which in turn is reciprocably mounted at its opposite sides on a frame 40 on a plurality of longitudinally spaced anti-friction rollers 41, 41. Said rollers have V-shaped engaging faces and are mounted on opposite sides of said frame 40, adjacent the forward and rear ends thereof, for rotation about vertical axes. V-shaped guide tracks 43, 43 are se-

cured to opposite sides of said transverse support and are engaged with the V-shaped faces of the rollers 41, 41, to provide a reciprocating support for the rear end of the reciprocating trough 15 on the support frame 40.

The bearing member 37 is journaled on a transverse support frame 44. Said support frame has outwardly opening V-shaped guides 45, 45 at opposite sides thereof, adapted to be engaged with V-shaped engaging faces of support rollers 46, 46, mounted on the stationary base 29, for rotation about vertical axes.

The connection from the support frame 40 to the stationary base 29 includes a guide frame 49 secured to the top of said base and projecting forwardly therefrom in horizontal planes spaced above said base. Said guide frame is provided with a transversely extending slot 50 adjacent its forward end, and with a longitudinally extending slot 51 spaced rearwardly from said transverse slot. Said slots 50 and 51 are adapted to be engaged by guide members 52 and 53, respectively, pivotally connected between a pair of spaced plates 54, 54 extending along the top and bottom sides of said guide frame. The ends of said plates in advance of said guide frame are herein shown as being secured to opposite sides of a hinged member 55, which is pivotally connected to said support frame by means of a transverse pivotal pin 56 mounted in an ear 57 depending from said support frame and interleaved by ears 48, 48 projecting forwardly from said hinged member. The arrangement of the slots 50 and 51 and the guide members 52 and 53 is such that said support frame will be supported and guided by said guide frame 49 for swinging movement with respect thereto in the path of travel of the reciprocating trough 15, as it pivots about the axes of the bearings 36 and 37.

A means is provided for centering the base 29 with respect to the stroke of the conveyer, to insure that the rollers 46, 46 and 41, 41 will supportingly engage their respective guide tracks during the entire stroke of the conveyer in all positions of the reciprocating trough with respect to the base 29. Said centering means is herein shown as being of a form which forms the subject matter of a companion application Serial No. 487,684, filed May 20, 1943, by Ernst R. Bergmann, now Patent No. 2,347,074, and includes a member 58 secured to and depending from the connecting trough 34 and having a pair of spaced apart inwardly extending stops 59, 59. Said stops are adapted to engage opposite faces of a stop 60, slidably mounted on the base 29 in a guide 61 extending transversely of said base and opening towards the inside thereof.

The distance between the stops 59, 59 is equal to the length of stroke of the conveyor plus the distance between opposite engaging faces of the stop 60, and in initially setting up the swivel, the shaker conveyor trough line is reciprocably driven for a few forward and return strokes. This will cause the stops 59, 59, engaging the stop 60, to move the base 29 along the ground until a point is reached where opposite engaging faces of said stop 60 are midway between the stops 59, 59, at the central portion of the stroke of the conveyor. At this point said base is secured in a stationary position on the ground by means of jacks 62, 62, adapted to be interposed between said base and the mine roof.

One of the jacks 62 is adapted to be set on a hinged member 63, pivoted to one end of the

base 29 for movement about an axis extending longitudinally of said base. The opposite end of said hinged member is pivotally connected to a pair of parallel spaced links 64, 64, which are pivotally connected to a link 65, extending along the upper surface of the base 29 and herein shown as having the stop 60 formed integral therewith. A spring 66 is interposed between the inner side of said stop and an end wall 68 of the guide 61, to urge said stop in a direction to be engaged with the spaced stops 59, 59. Thus when said base has been properly centered with respect to the stroke of the conveyor and the jack 62 is set on the hinged member 63, said hinged member will be pivoted downwardly into engagement with said base, to hold said stop out of registry with the stops 59, 59.

Referring now to the mechanism for swinging the shovel 11 laterally along the ground, two winding drums 67, 67 are mounted on a base 69, which may be detachably secured to the base 29. Flexible feeding or draft devices such as cables 70, 70 are adapted to be wound on or payed off of said winding drums. Said winding drums are separately driven from a motor 71 in such a manner that one winding drum will wind in one draft device while the other winding drum pays out its draft device. The drive from said motor to said winding drums may be of a type somewhat similar to that shown and described in Patent No. 2,272,049, which issued to Loy D. Hagenbook on February 3, 1942, and is no part of my present invention, so will not herein be shown or described in detail.

The base 69 is adapted to rest on the ground on its own bottom and is detachably connected at its rear end to the stationary base 29, by means of a connecting member 72. Said connecting member is secured to and extends rearwardly from the left-hand rear corner of said stationary base 29 between the top of said base 69 and the underside of a connecting member 73, which is secured to and extends parallel to the top surface of said base. A pivotal pin 74, adapted to extend through said connecting members and the base 69, is provided to detachably connect said bases together. A tie rod 75 extends diagonally from the right-hand rear corner of said base 29 to the right-hand rear portion of the base 69, and is detachably connected to said bases by means of pivotal pins 76 and 77 extending through the bifurcated ends of said tie rod and through brackets 78 and 79, secured to and projecting from said bases 29 and 69, respectively.

The reaction and guide means for the flexible draft devices 70, 70, for causing said draft devices to laterally move the troughs 10 and 15 about the swivel 30, include a tubular arm 80 secured to each side of the support frame 40 and extending forwardly therefrom along said troughs 15 and 10, beyond the forward end of said trough 10. Said arms are each connected to one side of said support frame by means of clamping members 81, 81 extending around a sleeve 81a mounted at the rear end of said tubular arm. Said clamping members extend inwardly from said arm and are secured to the undersurface of the support frame 40 by means of nuts and bolts, indicated by reference characters 82, 82. A sheave bracket 83 is pivotally mounted at the rear end of each of said tubular arms and forms a mounting for a sheave 84, mounted thereon for rotation about a vertical axis. Each of said sheave brackets is mounted on the end of a tubular member 83a which is mount-

ed within said arm for pivotal movement with respect thereto about the axis of said arm. A stop 83b projects rearwardly from the sleeve 81a and is adapted to fit within a slotted portion 83c of said sheave bracket, to limit pivotal movement thereof. The center of the groove of said sheave is aligned with the longitudinal center of said tubular arm, so that a flexible cable passing therearound may be trained through the center 10 of the said tubular arm.

The forward ends of each of said tubular arms are supported between a pair of vertical rollers 85, 85 having convex engaging surfaces adapted to engage opposite sides of one of said arms. Said rollers are mounted between a forked support bracket 86, on vertical pivotal pins 87, 87. Said support bracket is herein shown as being secured to and projecting outwardly from a shaft 88, mounted in a forwardly projecting support portion 89 of the pivoted frame 27, and secured thereto by means of a nut 90 threaded on said shaft and abutting an inner side of said forwardly projecting support portion of said pivoted frame. The forward end of each arm is thus supported above the ground on the pivoted frame 27 of the feeding mechanism, which in turn is supported on its forward end by the extensible trough 10 in advance of the reciprocating trough 15, and which reciprocably moves with respect to said arm during reciprocation of the conveyer.

A sheave bracket 91 is mounted on the forward end of each arm 80 and has a sheave 92 mounted thereon. The groove of said sheave extends in a generally horizontal direction and is in alignment with the center of said tubular arm, to permit a flexible cable trained through said arm to be trained around said sheave and laterally from said arm. Said sheave bracket is mounted on the end of a sleeve 91a, which is pivotally mounted in the forward end of the arm 80 for movement about the axis of said arm, to permit said sheave to follow an uneven mine bottom. A stop 91b projects forwardly from said arm and is adapted to extend within a slot 91c formed in said sheave bracket, to limit pivotal movement of said sheave and bracket.

The flexible cable 70 connected with the right-hand winding drum 67 extends rearwardly from said winding drum around a guide sheave 93, 50 mounted adjacent the rear end of the base 69 in a sheave bracket 94. From said sheave said cable extends inwardly around a sheave 95 mounted in a sheave bracket 96 projecting inwardly from the base 69, beneath the trough 55 35. From thence said cable extends forwardly in an angular direction towards the right-hand side of the loading device and is guided in a sheave 97 mounted on the base 29. Said cable extends from said sheave around a sheave 99 mounted on a bracket 100, projecting laterally 60 from the guide frame 49, to and around the sheave 84 at the rear end of the right-hand tubular arm 80. From thence said cable is trained through said arm to and around the sheave 92 at the forward end of said support arm. Said cable is then trained laterally for connection to a fixed abutment remote from the shovel 11, such as a mine jack interposed between the mine floor and roof, for swinging said extensible trough 65 to the right upon the winding in of said cable by its associated winding drum 67.

The cable 70 on the other winding drum 67 extends rearwardly therefrom around a sheave 101 mounted in a sheave bracket 102, and inwardly from said sheave to and around a sheave 75

103, mounted in the bracket 96. From thence said cable extends forwardly to and around a sheave 104 mounted in a bracket 105, projecting laterally from the guide frame 49. From said last named sheave said cable extends around the sheave 84, at the rear end of the arm 80, through the center of said arm, to and around the sheave 92 at the forward end of said arm, and laterally therefrom to the left, for connection to a fixed abutment such as a mine jack interposed between the mine roof and floor, for feeding said extensible trough to the left upon the application of power to wind in said flexible cable.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a self-loading device for shaker conveyors and in combination with a shaker conveyer trough line, a reciprocating trough connected to the receiving end of said trough line, for lateral swinging movement with respect thereto, an extensible trough mounted for slidable movement along the ground and for extensible or retractible movement with respect to said reciprocating trough, feeding means connected with said reciprocating trough and having engagement with said extensible trough during certain strokes of the conveyer, for extensibly or retractibly moving said extensible trough with respect to said reciprocating trough, and means for laterally swinging said extensible and reciprocating troughs along the ground including a pair of flexible feeding members, a pair of rigid independent arms extending along the sides of said reciprocating and extensible troughs, a slidable connection between said arms and said reciprocating trough for supporting the forward ends of said arms above the ground, the forward ends of said arms forming reaction members for said flexible feeding members, to cause said flexible feeding members to laterally swing said extensible and reciprocating troughs when anchored to fixed abutments remote from said trough and power is applied to draw in either one or the other of said flexible feeding members.

2. In a self-loading device for shaker conveyors and in combination with a conveyer trough line including a swivel having a reciprocating trough communicating with the receiving end thereof, and laterally swingable with respect thereto, an extensible trough mounted for slidable movement along the ground and for extensible or retractible movement with respect to said reciprocating trough, feeding means connected with said reciprocating trough and having engagement with said extensible trough during certain strokes of the conveyer, for extensibly or retractibly feeding said extensible trough with respect to said reciprocating trough, and means for laterally swinging said extensible and reciprocating troughs about said swivel including a pair of flexible feeding members, a pair of rigid independent arms extending along the sides of said extensible and reciprocating troughs, said arms being connected to said swivel at their rear ends and being supported on said reciprocating trough adjacent their forward ends so as to extend in advance of said reciprocating trough and serving as non-re-

ciprocating reaction members for said flexible feeding members, to cause said flexible feeding members to laterally move said extensible and reciprocating troughs when anchored to fixed abutments remote from said arms and power is applied to draw in either one of the other of said flexible feeding members.

3. In a self-loading device for shaker conveyers and in combination with a shaker conveyer trough line including a swivel having a reciprocating trough communicating with the receiving end thereof and laterally swingable with respect thereto, an extensible trough mounted on the ground for extensible or retractible movement with respect to said reciprocating trough, means connected with said reciprocating trough and having engagement with said extensible trough during certain strokes of the conveyer, for extensibly or retractibly feeding said extensible trough with respect to said reciprocating trough, and means for laterally swinging said extensible and reciprocating troughs about said swivel including a pair of rigid independent arms extending along the sides of said extensible and reciprocating troughs, and supported above the ground on said reciprocating trough adjacent their forward ends so as to extend in advance of said reciprocating trough, direction changing devices on the forward ends of said arms, and a pair of flexible feeding members trained around said direction changing devices, said direction changing devices serving as non-reciprocating reaction members for said flexible feeding members, to cause said flexible feeding members to laterally swing said extensible and reciprocating troughs when anchored to fixed abutments remote from said arms, and power is applied to draw in either one or the other of said flexible feeding members.

4. In a self-loading device for shaker conveyers, a conveyer trough line having a swivel connected to the inby end thereof and including a stationary base, a trough pivotally connected to said base and projecting therefrom, a reciprocating trough pivotally connected to and communicating with said pivoted trough, an extensible trough having a ground engaging shovel communicating with and forming a support for its forward end and having a ground engaging shoe forming a support for its rear end, a slidale supporting connection between the forward end of said reciprocating trough and said extensible trough for supporting the forward end of said reciprocating trough on said extensible trough, feeding means connected with said reciprocating trough and having gripping engagement with said extensible trough during certain strokes of the conveyer, for extending or retracting said extensible trough with respect to said reciprocating trough, and means for feeding said extensible and reciprocating troughs laterally during reciprocation of the conveyer including a pair of flexible feeding members adapted to be attached to fixed abutments remote from said extensible trough, a rigid arm extending along each side of said extensible and reciprocating troughs, connections from the rear ends of said arms to said stationary base, and supporting connections between said reciprocating trough and the forward ends of said arms, for supporting the forward ends of said arms above the ground in advance of said reciprocating trough, said arms forming non-reciprocating reaction members for said flexible feeding members, to cause lateral swinging movement of said extensible and reciprocating

ing troughs, upon the drawing in of either of said flexible feeding members.

5. In a self-loading device for shaker conveyors, a conveyer trough line having a swivel connected to the inby end thereof and including a stationary base, a trough pivotally connected to said base and projecting therefrom, a reciprocating trough pivotally connected to and communicating with said pivoted trough, an extensible trough having a ground engaging shovel communicating with and forming a support for the forward end of said extensible trough and having a ground engaging shoe forming a support for its rear end, a slideable supporting connection between the forward end of said reciprocating trough and said extensible trough, for supporting the forward end of said reciprocating trough on said extensible trough, feeding means connected with said reciprocating trough and having gripping engagement with said extensible trough during certain strokes of the conveyer, for extending or retracting said extensible trough with respect to said reciprocating trough, and means for feeding said extensible and reciprocating troughs laterally during reciprocation of the conveyer including a pair of flexible feeding members adapted to be attached to fixed abutments remote from said extensible trough, a rigid arm extending along each side of said extensible and reciprocating troughs, connections from the rear ends of said arms to said stationary base, supporting connections between said reciprocating trough and the forward ends of said arms, for supporting the forward ends of said arms above the ground in advance of said reciprocating trough, and sheaves on the forward ends of said arms, about which said flexible feeding members are adapted to be trained, for swinging said trough sections laterally upon the drawing in of either of said flexible feeding members.

6. In a self-loading device for shaker conveyers and in combination with a conveyer trough line including a swivel having a reciprocating trough communicating with the receiving end thereof, an extensible trough mounted on the ground, for extensible or retractible movement with respect to said reciprocating trough, feeding means connected with said reciprocating trough and having engagement with said extensible trough during certain strokes of the conveyer, for extensibly or retractibly feeding said extensible trough with respect to said reciprocating trough, and means for feeding said extensible and reciprocating troughs laterally during reciprocation of the conveyer including a pair of rigid hollow arms extending along opposite sides of said reciprocating and extensible troughs, supporting connections between said base and the rear ends of said arms, for supporting said arms for lateral movement in the path of travel of said reciprocating and extensible troughs, slideable supporting connections between said reciprocating trough and said arms, for supporting the forward ends of said arms above the ground during reciprocation of the conveyer, and a flexible feeding device trained through each of said arms and adapted to be attached to fixed abutments spaced laterally from opposite sides of said extensible trough, for swinging said extensible trough laterally upon the drawing in of either of said flexible feeding members.

7. In a self-loading device for shaker conveyers and in combination with a conveyer trough line including a swivel having a reciprocating trough

communicating with the receiving end thereof, an extensible trough mounted on the ground for extensible or retractible movement with respect to said reciprocating trough, feeding means connected with said reciprocating trough and having engagement with said extensible trough during certain strokes of the conveyer, for extensibly or retractibly feeding said extensible trough with respect to said reciprocating trough, and means for feeding said extensible and reciprocating troughs laterally during reciprocation of the conveyer including a rigid hollow arm extending along each side of said extensible and reciprocating troughs, said arms being connected to said swivel at their rear ends for lateral swinging movement in the path of travel of said reciprocating and extensible troughs and being supported above the ground on said reciprocating trough at their forward ends, guide sheaves at the forward ends of said arms, and a flexible feeding device trained through each of said arms and around and laterally from said guide sheaves to fixed abutments spaced laterally from opposite sides of said extensible trough, said arms and guide sheaves forming non-reciprocating guide and reaction members for said fleexible feeding members, whereby drawing in of either one of said flexible feeding members will laterally swing said extensible trough about said swivel.

30 8. In a self-loading device for shaker conveyers, a conveyer trough line having a swivel connected to the inby end thereof and including a stationary base, a trough pivotally connected to said base and projecting therefrom, a reciprocating trough pivotally connected to and communicating with said pivoted trough, an extensible trough having a ground engaging shovel projecting from and forming a support for the forward end of said trough and having a ground engaging shoe forming a slideable support for the rear end of said trough, a slideable supporting connection between said trough and the forward end of said reciprocating trough for supporting the forward end of said reciprocating trough above the ground, feeding means connected with said reciprocating trough and having gripping engagement with said extensible trough during certain strokes of the conveyer, for extending or retracting said extensible trough with respect to said reciprocating trough, and means for feeding said extensible and reciprocating troughs laterally during reciprocation of the conveyer including a pair of rigid hollow arms extending along opposite sides of said reciprocating and extensible troughs and connected to said swivel at their rear ends for movement in the path of travel of said reciprocating and extensible troughs, a pair of anti-friction supporting members mounted on each side of said reciprocating trough in advance of the forward end thereof and forming reciprocating anti-friction supports for said arms, and a flexible feeding member trained through each of said arms and adapted to be trained laterally beyond the forward ends thereof, to fixed abutments remote from opposite sides of said extensible trough, for feeding said extensible trough laterally upon the drawing in of either one of said flexible feeding members.

9. In a self-loading device for shaker conveyers, a conveyer through line having a swivel connected to the inby end thereof and including a stationary base, a trough pivotally connected to said base and projecting therefrom, a recipro-

cating trough pivotally connected to and communicating with said pivoted trough, an extensible trough having a ground engaging shovel projecting from and forming a support for the forward end of said trough and having a ground engaging shoe forming a slidable support for the rear end of said trough, a slidable supporting connection between said trough and the forward end of said reciprocating trough for supporting the forward end of said reciprocating trough above the ground, feeding means connected with said reciprocating trough and having gripping engagement with said extensible trough during certain strokes of the conveyor, for extending or retracting said extensible trough with respect to said reciprocating trough, and means for feeding said extensible and reciprocating troughs laterally during reciprocation of the conveyor including a pair of rigid hollow arms extending along opposite sides of said reciprocating and extensible troughs and connected to said swivel at their rear ends, for movement in the path of travel of said reciprocating and extensible troughs, a pair of anti-friction supporting members mounted on each side of said reciprocating trough in advance of the forward end thereof, said anti-friction members forming anti-friction supports for said arms, and being reciprocably movable along the forward portion of said arms during reciprocation of the conveyor, a flexible feeding member trained through each of said arms, and a guide sheave on the end of each of said arms communicating with the hollow insides thereof, and forming reaction and guide means for training said flexible feeding members laterally to fixed abutments remote from said extensible trough section, for feeding said trough section laterally upon the drawing in of either of said flexible feeding members.

10. In a self-loading device for shaker conveyors, a conveyor trough line having a swivel connected to the inby end thereof and including a stationary base, a reciprocating trough communicating with said swivel and connected to said base for lateral movement with respect thereto, an extensible trough mounted for extensible and retractile movement with respect to said reciprocating trough, feeding means connected with said reciprocating trough and having engagement with said extensible trough, for extending or retracting said extensible trough with respect to said reciprocating trough, and means for feeding said extensible and reciprocating troughs laterally during reciprocation of the conveyor including flexible feeding members adapted

5 to be attached to fixed abutments spaced from opposite sides of said extensible trough, power means for drawing in said flexible feeding members, an independent arm extending along each side of said extensible and reciprocating troughs, said arms being connected with said base for lateral movement with respect thereto in the path of said reciprocating and extensible troughs, and slidable supporting connections between said reciprocating trough and the forward ends of said arms for supporting the forward ends of said arms in advance of said reciprocating trough, to cause said arms to form non-reciprocating reaction members for said flexible feeding members, for laterally swinging said extensible and reciprocating troughs, upon drawing in of either of said flexible feeding members.

15 11. In a self-loading device for shaker conveyors, a conveyor trough line having a swivel connected to the inby end thereof and including a stationary base, a reciprocating trough communicating with said swivel and connected to said base for lateral movement with respect thereto, an extensible trough mounted for extensible and retractile movement with respect to said reciprocating trough, feeding means connected with said reciprocating trough, for extending or retracting said extensible trough with respect to said reciprocating trough, and means for feeding said extensible and reciprocating troughs laterally during reciprocation of the conveyor including an arm extending along each side of said reciprocating trough beyond the forward end thereof, said arms being independent of each other and connected to said swivel at their rear ends for movement in the path of travel of said reciprocating and extensible troughs and each having a direction changing member on the forward end thereof, flexible feeding members adapted to be trained from said base along said arms around said direction changing members and laterally therefrom, to fixed abutments remote from opposite sides of said extensible trough, for feeding said extensible trough laterally, upon the drawing in of either one of said flexible feeding members, and reciprocating slidale support means for said arms on said reciprocating trough, for supporting the forward ends of said arms in advance of said reciprocating trough, so said arms may form non-reciprocating reaction members for said flexible feeding members during reciprocation of said reciprocating trough.
